(57) **CLAIM**

The ornamental design for a pushbroom, as shown and described.

DESCRIPTION

FIG. 1 is a front view of the pushbroom design of the present invention.

FIG. 2 is rear view of the pushbroom design of the present invention.

FIG. 3 is the top view of the pushbroom design of the present invention.

FIG. 4 is the bottom view of the pushbroom design of the present invention.

FIG. 5 is a side view of the pushbroom design of the present invention.

FIG. 6 is the opposite side view of the pushbroom design of the present invention; and,

FIG. 7 is an isometric view of the pushbroom design of the present invention.

The handle is shown broken away to indicate an unspecified length. The broken-line structure shown in all of the views is for illustrative purposes only and forms no part of the claimed design.
